UNITED STATES PATENT OFFICE

2,119,690

FACING FOR BUILDING CONSTRUCTIONS

Elmer L. Torstenson, Chicago, Ill.

Application November 6, 1935, Serial No. 48,528

2 Claims. (Cl. 72—18)

My invention relates to building constructions.

One of the objects of my invention is to provide an improved facing for building constructions embodying the use of a sheet of glass for 5 the exposed face, the facing having anchorage means for securing it to a plastic support.

A further object of my invention is to provide such a construction in which the anchorage means are secured to the sheet of glass by the 10 fusion of a layer of colored vitrifiable material.

A further object is to provide such a construction in which the coloring material will be protected.

A further object is to provide such a construction in which the facing will be securely anchored 15 to the support.

A further object is to provide such a construction which will be inexpensive to manufacture and durable in use.

20 Further objects and advantages of the invention will be apparent from the description and claims.

In the drawing, in which my invention is illustrated,

25 Figure 1 is a sectional view of a glass panel provided on its rear surface with a layer of colored vitrifiable material and anchorage means; and

Fig. 2 is a sectional view showing a somewhat 30 different form of construction.

Referring to the drawing in detail and first to Fig. 1, the construction shown comprises a facing for building constructions, including a sheet 1 of transparent, translucent, semi-opaque, or opaque 35 glass having a layer 2 of colored vitrifiable material fused to its rear surface and an anchorage material 3 for securing the facing to a plastic support, which anchorage material is secured in position by the fusing of the vitrifiable material. The layer 40 of colored vitrifiable material may be a coating of glass enamel originally in the form of a frit, produced by pouring molten glass from a melting furnace into a tank of water. This frit may then be finely ground and mixed with suitable

45 fluxes and coloring materials and then applied by wet process, as by means of a brush, spray gun, or screening process. By "wet process" is meant holding the enamel in suspension with water, alcohol, or oils, or a combination of these 50 liquids.

The anchorage material 3, which may be a grit coating consisting of finely-ground, light fire clay, may then be sieved upon the coating of vitrifiable material, after which the glass panel, with the coating of vitrifiable material and the anchorage

material, may be secured together as a unit by fusion, as by inserting it into a kiln or lehr at a suitable temperature. The vitrifiable material and the sheet of glass should have such fusing characteristics that the layer of vitrifiable material will fuse at a somewhat lower temperature than the sheet of glass, thus avoiding softening and bending of the sheet of glass. The particles of grit form an anchorage for the panel by means of which it may be secured to any suitable plastic 10 backing, as will be described in detail hereinafter.

It may sometimes be desirable to provide two layers of the colored vitrifiable material, the first layer being applied and fused to the sheet of glass, and the second layer, with the anchorage 15 material, being thereafter applied. This use of the two layers of vitrifiable material may be desirable when the material used is of a light color, in which case a single layer might permit the anchorage material to settle into the layer of 20 vitrifiable material a sufficient distance to mar the color effect. In Fig. 2 is shown a panel in which two layers of colored vitrifiable material are used. In this form the first layer 4 of vitrifiable material is applied and fused to the sheet 25 of glass substantially as described in connection with Fig. 1, except that the grit or anchorage material is omitted. After the first layer 4 of vitrifiable material has been fused on, the second layer of vitrifiable material and the grit anchorage material may be applied. In this form, the second coating and the anchorage material 30 may be applied in a somewhat different manner than that of Fig. 1. The frit 5 and the anchorage material 3 may be mixed together wet and then 35 poured onto the first coating 4 of vitrifiable material which has already been fused to the sheet of glass and the pane of glass with the two layers of vitrifiable material and the anchorage material inserted into the kiln for the second firing. 40 It is obvious that this method of mixing the anchorage material and frit together wet before application is applicable also where only one coating is applied.

In the claims where the word "color" is used, it 45 is to be construed to include black and white.

Further modifications will be apparent to those skilled in the art and it is desired, therefore, that the invention be limited only by the prior art and the scope of the appended claims.

Having thus described my invention, what I claim and desire to secure by Letters Patent is:

1. A facing tile comprising a sheet of light-permeable glass, a thin layer of relatively opaque colored vitreous enamel glaze integrally adhered 55

to the rear surface thereof and interfused therewith, and anchorage material partially imbedded in said layer and protruding therefrom to provide a key for bonding the tile to a building surface.

5 2. A facing tile comprising a sheet of transparent glass, a thin layer of relatively opaque colored vitreous enamel glaze integrally adhered

to the rear surface thereof and interfused therewith, and anchorage material partially imbedded in said layer and protruding therefrom to provide a key for bonding the tile to a building surface, said layer of vitreous enamel glaze having a lower fusing point than that of said glass sheet.

ELMER L. TORSTENSON.
